UNITED STATES PATENT OFFICE.

JOHN W. DIMOCK, OF CARBONDALE, PENNSYLVANIA.

NECKTIE-FASTENER.

SPECIFICATION forming part of Letters Patent No. 278,690, dated June 5, 1883.

Application filed April 5, 1883. (No model.)

To all whom it may concern:

Be it known that I, JOHN W. DIMOCK, a citizen of the United States, residing in the city of Carbondale, county of Lackawanna, and 5 State of Pennsylvania, have invented a new and Improved Necktie-Fastener, of which the following is a specification.

My invention relates to an improvement in necktie-fasteners, and the object of my improvement is to afford a simple and convenient method for keeping the necktie in position when placed around the collar, and yet without injuring the necktie. I attain this object by the necktie-fastener illustrated in the accompanying drawings, in which—

Figure 1 represents a front view of the improved necktie-fastener. Fig. 2 represents the pin D, as described in the specification.

The nature of my invention consists in the 20 construction, from block-tin or other metal, of the new and improved necktie-fastener, having a base-bar, A, from each end of which and at right angles runs a side bar, B B, on a plane surface, and from center of base-bar, A, a center bar, C, at right angles with it, with slightly deflected surface to end of bar to permit entrance of collar in the deflection between bars B B and C, and the pin D reversed or bent back from the end of center bar, C, being an

extension of or application to the center bar, 30 C, and extending to or toward the base-bar, A, which pin D is inserted in cravat or necktie, fastening tie and collar together and holding the necktie in place.

The manner of using the necktie-fastener is 35 as follows: Place the collar in the deflection between the side bars, B B, and C. Then adjust the necktie, and when in proper position insert the pin D into it.

The advantages of my invention are, first, 40 that it is a simple and convenient method for fastening the necktie to the collar; second, that when properly adjusted it will keep its position under all circumstances; third, that it will retain its position without mutilating the necktie; fourth, that when in place it is entirely 45 hidden from view and is durable and reliable.

What I claim as my invention, and desire to secure by Letters Patent, is—

The metal necktie-fastener with base-bar A, 50 side bars, B B, center bar, C, and pin D, all constructed, arranged, and operated as and for the purposes set forth above.

J. W. DIMOCK.
